UNITED STATES PATENT OFFICE.

JOHAN FREDRIK BJÖRKGRÉN, OF HOLMGATAN, FALUN, SWEDEN, ASSIGNOR, BY
MESNE ASSIGNMENTS, TO REGULAX ENGINE CORPORATION, A CORPORATION
OF DELAWARE.

REGULATING MECHANISM FOR CONTROLLING THE SUPPLY OF FUEL TO INTERNAL- COMBUSTION ENGINES.

1,410,360.

Specification of Letters Patent. Patented Mar. 21, 1922.

Application filed January 13, 1920. Serial No. 351,158.

To all whom it may concern:

Be it known that I, JOHAN FREDRIK BJÖRKGRÉN, citizen or subject of the King of Sweden, residing at Holmgatan 2, Falun, 5 Sweden, have invented certain new and useful Improvement in Regulating Mechanism for Controlling the Supply of Fuel to Internal-Combustion Engines, of which the following is a specification.

10 The present invention relates to an arrangement for controlling the fuel supply to internal combustion engines. The arrangement in question is extremely sensitive and always supplies the motor with a 15 quantity of fuel exactly corresponding to the speed and load of the motor.

The invention is principally characterized by a sleeve which is slidably but not rotatably mounted on the motor shaft or 20 on a shaft connected therewith, the said sleeve being provided with a notch extending obliquely with respect to the axis of the shaft, a ring being retained by the said notch so as to swing to and fro on account 25 of the oblique position of the notch, which motion is imparted to the plunger of the fuel pump, said plunger being connected directly or indirectly with the said ring. As the sleeve provided with the ring is dis- 30 placed to different positions on the shaft, the relative position is changed between the ring and the pump plunger or between the ring and a member connecting the ring with the pump plunger, whereby motion is be- 35 ing transmitted to the latter. Thus the length of stroke of the plunger and the quantity of the fuel supplied are also changed.

The displacement of the ring-carrying 40 sleeve on the shaft takes place automatically on variations in the speed of the motor. This is due to the ring being connected with and actuated by a weight which is slidably mounted in a disk-like member attached to 45 the shaft and acted upon by springs tending to move the weight inwardly against the action of the centrifugal force thereon. The sleeve is displaced in the one or the other direction by means of wedges or the 50 like arranged at the weight.

The accompanying drawing shows an embodiment of the invention by way of ex-

ample, Fig. 1 being a longitudinal section of the arrangement and Fig. 2 an end view thereof.

55 1 is the motor shaft, attached to which is a disk-like member 2. In the latter the weight 3 is slidable in a radial direction, the same being guided by a pin 4 fastened to the disk, which pin is surrounded by a 60 spring 5 tending to move the weight inwardly toward the centre of the disk. Attached to the weight are two wedges 6 situated one on each side of the shaft 1 and bearing against the oblique end face of a 65 sleeve 7 which is slidably but not rotatably mounted on shaft 1. The sleeve 7 is actuated by a spring 8 so as to form contact with the said wedges. In the sleeve 7 there is provided an oblique notch 9 encircling the 70 sleeve, said notch having secured therein a ring 10. The latter is provided with a projection 11 abutting against the one arm 12 of a bell-crank lever, whose other arm 13 abuts against the pump plunger 14.

75 In operation the ring 10 is caused to oscillate on account of the oblique notch 9, and its projection 11 moves to and fro in the direction of the axis of the shaft thereby actuating the bell-crank lever 12, 13 by 80 means of which the plunger of the fuel pump is brought to move to and fro. The speed of the motor being normal, the weight is kept in a normal position through the centrifugal force acting thereon, said position of the weight determining the normal 85 position of the sleeve 7, that is to say the normal position between the projection 11 of the ring 10 and the arm 12 of the bell-crank lever. If the motor is slowing down, 90

the weight will be displaced inwardly through the influence of the spring 5 and thereby actuates the sleeve 7 through the wedges 6 so that the sleeve is moved to the right in the drawing, that is to say the projection 11 of the ring 10 is approached to the arm 12. Thus, the period during which the projection 11 acts on the arm 12 is extended and, consequently, the length of stroke of the pump plunger and thus the 100 quantity of fuel supplied will be increased in a corresponding degree. If on the other hand, the speed of the motor increases, conditions will be reversed, the weight then

moving outwardly by the increasing centrifugal force, whereby the sleeve 7 is displaced to the left, thus withdrawing the ring-projection 11 from the arm 12 so that the length of the pump stroke is diminished.

To regulate the length of the suction stroke of the pump, notwithstanding the automatic control brought about by means of the arrangement above described, there is provided in the fixed part 15 a rotatably mounted eccentric 16 adapted to be adjusted by hand, the arm 13 striking said eccentric when it moves back on the suction stroke of the plunger 14. The magnitude of this back motion of the plunger may be regulated by turning the eccentric more or less.

What I claim as new and desire to secure by Letters Patent of the United States is:—

1. A regulating mechanism to control the supply of fuel for internal combustion engines, characterized by a sleeve slidably and non-rotatably mounted on a motor driven shaft, the said sleeve being provided with a recess extending obliquely with respect to the axis of the shaft, a ring arranged in said recess so as to move to and fro on account of the oblique position of the recess, and

means for utilizing the movement of the ring in the operation of a fuel pump.

2. A regulating mechanism to control the supply of fuel for internal combustion engines comprising a motor driven shaft, a sleeve carried by and non-rotatable relative to the shaft and adapted for longitudinal displacement thereon, a non-rotatable ring mounted upon the sleeve obliquely with respect to the axis of the shaft whereby oscillatory movement of the ring is effected incident to the rotation of the shaft and sleeve, an arm carried by the sleeve, a lever actuated by the arm and adapted to drive a power pump, a centrifugally controlled means arranged to displace the sleeve longitudinally upon the shaft to vary the stroke of the lever.

3. A regulating mechanism according to claim 1 characterized by a lever actuated by the ring and an adjustable abutment coacting with the lever to limit the movement thereof.

In testimony whereof I affix my signature in presence of two witnesses.

JOHAN FREDRIK BJÖRKGREN.
